UNITED STATES PATENT OFFICE.

JAMES A. MARR, OF BRIDGEPORT, CONNECTICUT.

VALVE FOR INTERNAL-COMBUSTION ENGINES.

1,129,582.

Specification of Letters Patent. Patented Feb. 23, 1915.

Application filed June 2, 1913. Serial No. 771,184.

To all whom it may concern:

Be it known that I, JAMES A. MARR, a citizen of the United States, residing at Bridgeport, county of Fairfield, State of Connecticut, have invented an Improvement in Valves for Internal-Combustion Engines, of which the following is a specification.

This invention relates to internal combustion engines adapted for general use and especially adapted for use in motor vehicles, and the invention has for its object to simplify and cheapen the construction, to reduce the number of parts and to greatly improve the operation of this type of engines.

I have illustrated the invention as applied to a four-cycle engine and accomplish the desired results by the use of a single valve having continuous rotary movement, each rotation corresponding with the series of cycles, said valve having ducts extending longitudinally thereof, so that both the intake and the exhaust gases enter and leave the valve at different transverse planes, and said valve having an air passage its entire length so that it may be kept cool by passing a current of air through it.

With these and other objects in view I have devised the novel structure which I will now describe, referring to the accompanying drawings forming a part of this specification, and using reference characters to indicate the several parts.

Figure 1 is a vertical transverse section of my novel engine, the valve and certain other parts being shown in elevation; Fig. 2 a section on the line 2—2 in Figs. 1 and 8 looking in the direction of the arrows; Fig. 3 an elevation of the valve detached; Figs. 4, 5, 6 and 7 are transverse sections on the lines 4—4, 5—5, 6—6 and 7—7, respectively, in Fig. 3, looking in the direction of the arrows; Fig. 8 a plan view of my novel engine; Fig. 9 a longitudinal section of the valve detached; Fig. 10 an end elevation of the valve as seen from the left in Fig. 9; Figs. 11, 12, 13 and 14 are diagrammatic views illustrating the position of the valve and crank shaft at the mid-portion of each cycle; Fig. 15 a view partly in elevation and partly in longitudinal section illustrating a modification in the arrangement of the ducts in the valve and consequently of the air passage which is continuous but not straight and not central; and Figs. 16, 17, 18, 19 and 20 are transverse sections of the modified form of valve on the lines 16—16, 17—17, 18—18,

19—19 and 20—20, respectively, in Fig. 15, looking in the direction of the arrows.

30 denotes the valve chamber, 31 the valve, 32 cylinders, 33 pistons, 34 the connecting rods, 35 the cranks, 36 the crank shaft, 37 the fly wheel, 38 a sprocket wheel on the crank shaft, 39 a sprocket wheel on the valve, 40 a sprocket chain by which rotation is imparted to the valve from the crank shaft, 41 the crank chamber, 42 an intake pipe, 43 exhaust pipes, and 44 water chambers surrounding the cylinders, the valve, and exhaust passages which lead from the valve chamber to the exhaust pipes, (see dotted lines, Fig. 2).

In Figs. 1 to 10, inclusive, and in Fig. 14, the parts are in a position in which both pistons are at the mid-portion of a cycle, the left piston in Fig. 1 is being driven forward by an explosion and the right cylinder in Figs. 1 and 14 is moving backward and exhausting.

In the form illustrated in Figs. 1 to 10, inclusive, the valve is provided with a central air passage 45 extending straight through it. There are two ports for the ingress and two for the egress of the gases corresponding with each cylinder, and ducts connecting said ports. Commencing with the gas in the intake pipe it enters the valve through a port 46 in the valve and passes into an intake duct 47 (see Figs. 2, 5, 9 and 11). From this duct it passes through a port 48 in the valve and a passage 49 in the valve chamber to the right cylinder (see Fig. 11) in which the piston is moving forward. This comprises the first cycle. The second cycle, which is the backward movement of the piston, as in Fig. 12, compresses the gas which is then exploded and the piston driven forward as in Fig. 13, which comprises the third cycle. The fourth cycle comprises the backward movement of the piston, as in Fig. 14, which drives the gas out of the cylinder and through passage 49 in the valve chamber and a port 50 in the valve into an exhaust duct 51 in the valve, from whence it passes through a port 52 in the valve to the right exhaust pipe 43. The ducts 47 and 51 are separated by webs 51' and their ends are closed by webs 52', as shown.

The first cycle of the left cylinder corresponds with the second cycle of the right cylinder, consequently when compression is taking place in the right cylinder the left cylinder will be taking gas from pipe 42 which will enter the valve through a port

53 in the valve and pass into an intake duct 54 (see Figs. 6, 9 and 11). From this duct it passes through a port 55 in the valve and a passage 56 in the valve chamber to the left cylinder (see Fig. 11, in which for the sake of clearness two sets of numbers appear in order to describe clearly the passage of gas through the valve to each cylinder and from each cylinder back through the valve to the corresponding exhaust pipe). The cycles are repeated in connection with the left cylinder as with the right, the first cycle comprising the intake of gas, the second the compression, the third the explosion and the fourth the exhaust. The backward movement of the left piston in the fourth cycle drives the gas out of the cylinder and through a passage 56 in the valve chamber and a port 57 in the valve into an exhaust duct 58 in the valve, from whence it passes through a port 59 in the valve to the left exhaust pipe 43 (see Figs. 7, 9 and 14). The ducts 54 and 58 are separated by transverse webs 58' and their ends are closed by webs 59'. It must be borne in mind that one intake pipe supplies gas to both cylinders but each cylinder exhausts through a separate pipe. Port 46 and port 48, which supply gas to the right cylinder, are wholly out of alignment, that is in different transverse planes of the valve and are connected by intake duct 47 in the valve. The same is true of port 53 and port 55 which supply gas to the left cylinder and are connected by intake duct 54 in the valve. The exhaust from the right cylinder is through ports 50 and 52 which are in different transverse planes of the valve and are connected by exhaust duct 51 in the valve. The exhaust from the left cylinder is through ports 57 and 59 which are in different transverse planes of the valve and are connected by exhaust duct 58 in the valve. Each of the two intake ducts is therefore only operative to deliver gas to the corresponding cylinder and each of the two exhaust ducts is only operative to exhaust gas from the corresponding cylinder.

It will of course be understood that the body of the engine may be of any ordinary or preferred construction or design. I have shown the valve casing as made in two parts for convenience in grinding, fitting and adjusting the valve and the bearings. It is furthermore wholly immaterial what special mechanism is used to impart rotary movement to the valve.

An important feature of the invention is the longitudinal air passage through the valve by which it is kept cooled. In order to facilitate the passage of air therethrough I extend one end of the valve to form a fan chamber and place a fan 60 therein which is rigidly secured to the wall of the chamber, the action of which is to draw a current of

air through the longitudinal opening when the valve is rotated.

The form of valve illustrated in Figs. 15 to 20, inclusive, differs only in details of construction. The intake ports instead of opening into independent ducts as in the other form open into a single duct which communicates alternately with ports leading to the cylinders. The arrangement of the walls of the ducts in this form leaves the air passage continuous as before but not central and not straight, as before. The ports in the valve are all arranged precisely as before. Ports 46 and 53 open into a single duct 61. From this duct the gases pass alternately through ports 48 and 55 to the right and left cylinders. From the right cylinder the gases pass through exhaust duct 62 and port 52 to right exhaust pipe 43. From the left cylinder the gases pass through exhaust duct 63 and port 50 to left exhaust pipe 43. The continuous air passage which is tortuous is indicated by 64. In all engines of this type the cylinders are of course in pairs. In a four, six or more cylinder engine a single valve may be used extending across the top of all the cylinders, or if preferred each pair of cylinders may have a valve independently operated in any suitable manner. The engine cylinders may be cast singly, in pairs or *en bloc*, as preferred, it being understood that these details of construction may be varied to suit the requirements of use or the judgment of the manufacturer.

Having thus described my invention I claim:

1. In an engine of the character described, a pair of explosion cylinders; a valve chamber extending across the explosion cylinders and provided near its ends with gas outlet ports leading into the upper ends of the cylinders, and between the gas outlet ports with a common gas inlet means; pistons mounted to reciprocate within the cylinders; a tubular rotatable valve mounted within the valve chamber and having a longitudinal air-passage extending through the opposite ends thereof for the free circulation of air, said tubular valve being provided between the gas outlet ports of the valve chamber with two transversely aligned spaced gas inlet ports adapted to be successively brought into registration with the common gas supply means, the valve inlet ports leading into the valve outlet ports which are arranged upon opposite sides thereof, by means of longitudinal ducts arranged within the tubular valve, said valve outlet ports being adapted for registration at different times with the valve chamber outlet ports, said tubular valve being provided with inner exhaust ports spaced from and in alignment with the valve outlet ports to be brought into registration at different times.

with the valve chamber outlet ports, said valve inner exhaust ports having free communication with longitudinal ducts arranged within the tubular valve and discharging through outer valve exhaust ports; and means to rotate the tubular valve.

2. In an engine of the character described, a pair of explosion cylinders; a valve chamber extending across the explosion cylinders and provided near its ends with gas outlet ports leading into the upper ends of the cylinders, and between the gas outlet ports with a common gas inlet means; a tubular rotatable valve mounted within the valve chamber and having a longitudinal air passage extending through the opposite ends thereof for the free circulation of air, said tubular valve being provided between the gas outlet ports of the valve chamber with two transversely aligned spaced gas inlet ports adapted to be successively brought into registration with the common gas supply means, said tubular valve being provided upon opposite sides of the valve inlet ports with valve outlet ports adapted to be moved into registration with the valve chamber outlet ports and having means of communication with the valve inlet ports arranged interiorly of the tubular valve, said tubular valve being provided with inner exhaust ports spaced from and in alignment with the valve outlet ports and adapted to be brought into registration with the valve chamber outlet ports, said tubular valve being provided with outer exhaust ports having communication with the inner exhaust ports by interior ducts; and means to rotate the tubular valve.
3. In an engine of the character described, a pair of explosion cylinders; a valve cham-

ber extending across the explosion cylinders and provided near its ends with gas outlet ports leading into the upper ends of the cylinders, and between the gas outlet ports with a common gas inlet means; a rotatable valve mounted within the valve chamber and embodying inner and outer spaced tubular shells, the inner shell having both ends open for the free passage of air therethrough for the purpose of cooling the valve, said outer tubular shell being provided between the outlet ports of the valve chamber with two transversely aligned spaced gas inlet ports adapted to be successively brought into registration with the common gas supply means, the outer tubular shell being provided upon opposite sides of the valve inlet ports with valve outlet ports adapted to be moved into registration with the valve chamber outlet ports and having communication with the valve inlet ports by non-communicating ducts arranged between the outer and inner tubular shells, said outer tubular shell being provided with inner exhaust ports spaced from and in alignment with the valve outlet ports and adapted to be brought into registration with the valve chamber outlet ports, said outer tubular shell being provided with outer exhaust ports having communication with the inner exhaust ports by non-communicating ducts arranged between the inner and outer tubular shells; and means to rotate the tubular valve.

In testimony whereof I affix my signature in presence of two witnesses.
